CLAIM

The ornamental design for goggles, as shown and described.

DESCRIPTION

FIG. 1 is a top, front, right side perspective view of goggles showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged detail view of a portion of FIG. 1. The dot-dash broken lines shown in the figures define boundaries of the claimed design and form no part thereof. All other broken lines shown in the figures represent unclaimed portions of the goggles and form no part of the claimed design.
